GUARDED SAFETY PIN CONSTRUCTION

Frederick J. Van Dusen, Jackson Heights, N. Y.,
and Thomas Cymmer, Jersey City, N. J.

Application March 20, 1950, Serial No. 150,602

3 Claims. (Cl. 24—156)

1

Our invention relates to a guarded safety pin construction and more particularly to a novel guard for covering the pointed end of a safety pin in the open pin position.

In ordinary safety pins the pointed end of the pin is exposed while the pin is not in use and is in the open pin position. The open safety pin therefore presents a sharp point which may scratch or puncture the skin while the pin is being handled and being applied to materials to be secured. Ordinary safety pins used in fastening the clothing of infants present considerable hazard when they are unfastened, handled, or even swallowed. It has been proposed to protect the point of an unlocked safety pin by providing a recess in the top of the keeper as shown in the patent issued to Joseph Morley, 2,145,313, dated January 31, 1939, and it has also been proposed to protect the unlocked point by a pivoted keeper or cover as shown in the patent issued to John Rosenquist, 2,089,576, dated August 10, 1937.

It is an object of this invention to provide a guarded safety pin construction in which the pointed end spring biased to an open pin position lies under a protecting flange or shoulder which prevents the point from causing accidental injury.

It is another object of this invention to provide a guarded safety pin construction in which the point guard projects upwardly from the conventional keeper which secures the pointed end in the closed pin position.

It is a further object of this invention to provide a guard construction for the pointed end of an open safety pin in which the guard construction is integral with the keeper which secures the pointed end in the closed pin position.

It is a still further object of this invention to provide a point guard construction which may be used with safety pins of various forms of spring constructions.

Other objects and advantages of this invention will be readily apparent from the following description of preferred embodiments illustrated in the accompanying drawings wherein:

Figure 1 is an elevational view of a safety pin embodying our invention, the pin being shown in the closed position and the open pin position being indicated in dotted lines.

Figure 2 is a sectional view taken on line 2—2 of Figure 1.

Figure 3 is an elevational view of a modified form of safety pin embodying our invention, the pin being shown in the closed position.

Figure 4 is a plan view of the pin shown in Figure 3.

Figure 5 is an end elevational view of the pin shown in Figure 3.

2

Figure 6 is a plan view of another modification of a safety pin embodying our invention.

Figure 7 is an elevational view of the pin shown in Figure 6.

Figure 8 is an end elevational view of the pin shown in Figure 6.

Figure 9 is an end elevational view of a modified form of safety guard and keeper construction, with the pin member shown in section and in the open pin position.

Referring to the drawings for the purposes of illustration, the safety pin shown in Figures 1 and 2 includes a keeper 10, a single piece of pin wire having a base portion 11, a curved spring portion 12 and a pin portion 13. The pin 13 has a pointed end 14 indicated in dotted lines in the keeper 10, and in the open pin position the pin portion 13 takes the dotted line position 13'. The keeper 10 may be stamped from sheet metal and includes a lower portion 15 surrounding and firmly gripping the curved end of the base portion 11, the curved end of the latter being indicated in dotted lines in Figure 1. The keeper 10 may have an upwardly extending portion 17 to guide the point 14 into the channel or groove 18 of the keeper in the closed pin position. The keeper 10 is provided with an upwardly projecting portion or guard member 20 having shoulders 21 at the top thereof. When the pin is in the closed position, as shown in Figure 1, the pointed end 14 of the portion 13 is seated in the channel 18 of the keeper 10. When the pin is in the open position, the spring 12 holds the point 14 against the side of the extension 20, just below the underside of a shoulder 21 where the point 14 is guarded or covered against accidental engagement with the skin, fabrics, or other objects. The point is protected by a shoulder 21 regardless of the side to which the point is shifted in opening the pin by moving the point 14 out from the keeper channel 18. The spring action of the curved portion 12 of the pin should hold the point 14 just below the underside of a shoulder 21 in the open pin position.

The modification shown in Figures 3, 4 and 5 is generally similar to that shown in Figures 1 and 2 except that the upper portion 25 of the spring wire is provided with one or more loops 26 in planes substantially at right angles to the vertical plane of the pin. The loops 26 serve to provide a desirable spring action between the lower and upper portions of the pin to maintain the point 27 in the keeper 28 in the closed pin position, and to keep the point 27 against the keeper extension or guard member 30 just below a shoulder 29 of the keeper extension 30 in the open pin position.

In the modification illustrated in Figures 6, 7 and 8, the keeper and guard construction is similar to those shown in the preceding figures, and

the spring wire 32 is provided with a coiled portion 33 extending at an angle to the vertical plane of the pin. In both the Figure 3 and Figure 7 constructions, the spring coils 26 and 33 serve as stops on the upper pointed leg of the pin to limit the distance to which the pointed end may be inserted through fabric materials or the like.

A safety pin keeper having a modified guard construction is shown in section in Figure 9, wherein the upward extension or guard member 35 of the keeper 36 is provided with a rolled over upper edge 37 on either one side or the other. The rolled edge 37 provides a protecting cover for the pointed end 14 of the pin 13, 25 or 32 when the pin is in the open-pin position. The keeper 36 with the rolled guard edge 37 may be used with pins of any of the spring forms shown in Figures 1, 3, 7, or the like.

While the keeper and guard constructions illustrated are conveniently formed from sheet metal, they may be formed of molded metal or plastic materials, and the projecting extension carrying the shoulders 21 or 29 or the curved edge 37 may be integral with or separate from the keeper members 10, 28, or 36.

Other modifications as well as advantages of our invention will be readily apparent to those skilled in the art, and it will be apparent that many changes in minor details, proportions and design may be carried out with the scope of the appended claims.

We claim:

1. A safety pin comprising in combination, a base portion and a pin portion connected together by a loop portion and formed of resilient wire, said pin portion having a pointed free end

and being resiliently biased away from said base portion by said loop portion, a keeper secured to said base portion remote from said loop portion, said keeper having a channel portion spaced from and facing said base portion to receive said pointed end in the closed pin position, a guard member of smooth outline carried by said keeper and projecting therefrom in a direction away from said base portion, and a shoulder at the outer edge of said guard member remote from said keeper engaged by said pointed end in the open pin position to partially cover said pointed end.

2. A safety pin construction as defined in claim 1, said guard member being substantially flat and said shoulder projecting from said guard member edge on both sides thereof.

3. A safety pin construction as defined in claim 1, said guard member having a curved edge remote from said keeper and said shoulder being curved and extending along a portion of said curved edge.

FREDERICK J. VAN DUSEN.
